United States Patent

Des. 236,683
Patented Sept. 9, 1975

236,683

DOOR VIEWER PLATE

Raymond U. H. Tegner, Lodi, Wis., assignor to Amerock Corporation, Rockford, Ill.

Filed Dec. 26, 1973, Ser. No. 427,840

Term of patent 14 years

Int. Cl. D8—09

U.S. Cl. D8—179

FIG. 1 is a front view of a door viewer plate.
FIG. 2 is a side view of the plate as seen from the right of FIG. 1.

FIG. 3 is an end view as seen from the bottom of FIG. 1.

FIG. 4 is a sectional view taken along the line 4—4 in FIG. 1.

I claim:

The ornamental design for a door viewer plate, as shown.
